UNITED STATES PATENT OFFICE.

CARTER W. SINGLETERRY, OF DOWNERS GROVE, ILLINOIS, ASSIGNOR OF ONE-FOURTH TO EDWARD D. SCHUTH AND ONE-FOURTH TO WILLIAM F. SCHUTH, BOTH OF CHICAGO, ILLINOIS.

CLOTHES-DRIER.

1,269,012.

Specification of Letters Patent. Patented June 11, 1918.

Application filed November 17, 1916. Serial No. 131,815.

To all whom it may concern:

Be it known that I, CARTER W. SINGLETERRY, a citizen of the United States, residing at Downers Grove, in the county of Du-
5 page and State of Illinois, have invented a certain new and useful Improvement in Clothes-Driers, of which the following is a specification.

This invention relates to clothes driers.

- 10 The object of the invention is to provide mechanism for suspending articles generally, and particularly household articles, such as towels, clothing, and the like for ready drying which mechanism is, when not 60 in use, collapsible into a very small space so as to be entirely out of the way, the scheme being to locate the device in rooms 65 or passageways ordinarily used for other purposes.
20 The invention consists in a device capable of carrying out the foregoing objects, which can be very easily and cheaply made and installed, which is satisfactory in operation, and not readily liable to get out of 70 order. More in detail, the invention consists in the particular features and details of construction hereafter more fully set forth in the specification and claims.

Referring to the drawings, in which similar numerals indicate the same parts throughout the several views,

Figure 1 is a perspective view of mechanism illustrating this invention in its preferred form, the same being in collapsed 80 position in which it occupies a minimum of space and in which the clothes drying bars are substantially concealed from view, thus making the device unobjectionable for use in small apartments of the convertible type 85 where every inch of space counts and attractiveness of appearance of things is of prime consideration.

Fig. 2 is a perspective view of the device shown in Fig. 1, extended both vertically and horizontally and ready for use.

Fig. 3 is a front view of the device with the parts shown in the position of Fig. 1, the outer front plate being removed.

Fig. 4 is a changed position view of the 50 parts of Fig. 3, the clothes hanging bars being extended for use as in Fig. 2.

Fig. 5 is a plan detail view on the line 5—5 of Fig. 4.

Fig. 6 is a sectional plan view on the line 55 6—6 of Fig. 4.

Generally speaking, the mechanism of this invention includes a vertically extensible case member 10, mounted on a stationary support 12, which may be the wall of the room, carrying a plurality of horizontally extensible and locatable clothes bars 14. The idea is to provide adjustment for the clothes bars 14 not only in a horizontal plane, but in any desired position vertically between that shown in Fig. 4 and that shown in Fig. 2, so that the operator may selectively adjust the bars 14 vertically either for convenience in hanging clothes thereon, or with reference to a convenient drying device, the clothes bars 14 being, 70 when not in use, concealable inside of the case member 10.

The stationary support or wall 12, heretofore referred to, has rigidly attached to it by any suitable means a parallel plate 16 75 separated therefrom by a space 18 so that there is ample room therein for the location and operation of a pair of sprocket chain gears 20 and 22, having passing over them a sprocket chain 24. One of these 80 gears, as 22, is operated by any suitable means, as for instance a hand crank 26 and may be locked in any desired position by any suitable means, as for instance a 85 slideable forked latch bar or catch 28 adapted to detachably engage any non-circular member, as for instance nut 30, rigidly connected to crank arm 26 and gear wheel 22. This latch member 28 is provided with a handle 32 for manipulation backward and forward 90 by the hand of the operator through a suitable supporting housing 34.

The member 16, heretofore referred to, is made in channel-shaped form with flanges 16^a, as shown, extending toward the support 95 12, thus providing a protection for the gears 20 and 22, heretofore described.

The case member 10, heretofore described, is made to fit and to slide over the member 16 between the position of Fig. 1 and that 100 of Fig. 2, and for this purpose is provided at its lower portion with a back plate 36, rigidly secured to the side flanges 10^a of the member 10. From this back plate 36 is provided a rigid connection member 38 105 rigidly secured by any suitable means, as for instance bolt device 40, to the chain 24, heretofore described. The result of this construction is that as the operator, after releasing catch 28 rotates crank 26, he moves 110

the chain 24 to positively move the member 10 and attached parts up or down, as desired, to any desired position, and that on reaching said position he can lock all the parts in that position through the obvious use of the latch 28.

The upper portion of the case member 10 is provided with a cap or hood device 42 of generally semi-circular horizontal cross-section extending, as shown, forwardly from the face of member 10. In the curved face 44 of this cap is cut a horizontally elongated slot 46 through which the clothes bars 14 project in the manner shown in the drawings 10 and take bearing on their upper sides on a supporting rib 48 formed on the underside of the upper plate of the hood 42, while they take bearing on their undersides on the lower edge 50 of the slot 46.

Mounted inside of the hood 42 is a suspending frame of peculiar form, in the case here illustrated made of wire on which loops 52 on the inner ends of the clothes bars 14 are adapted to slide. This frame 20 is made up of an upper portion 54 lying in the same horizontal plane as the slot 46 heretofore described, and is provided in its central portion with a curved member 54^a concentric with the curved front face 25 44 of the hood, as shown in detail in Fig. 5, the result being that the clothes bars 14 when moving to extended position can move in the arc of a circle horizontally along this member 54^a. The frame also includes a 30 horizontal bar 56 extending transversely of the member 10, as clearly shown in Fig. 3, so that when the device is collapsed the clothes bars 14 hang vertically, as shown in that figure. The two parts 54 and 56 of 35 the frame are connected together by a vertical loop 58 adapted to be traversed by the loops 52 on the clothes bars 14 as they are moved from the storage position of Fig. 3 inside the case 10 up to extended position 40 shown in Figs. 2 and 4. At the juncture of portions 56 and 58 of the frame is an offset 45 60 preferably extending vertically from member 56 to 58 so that the suspended loops 52 cannot move up this offset 60 except by the hand manipulation of the operator, thus insuring the clothes bars 14 staying inside the case 10 when once put there. The loops 52, and consequently the clothes bars 14, are normally moved toward this member 60 by 50 a suitable spring 62.

It is obvious from the drawings that the flange 10^a on the left hand side of member 10 is cut away sufficiently, as clearly appears in Fig. 1, to allow the entrance of the 60 clothes bar members 14 into and out of the storage space 64, which exists as shown in the drawings between the front plate 10 of the vertically movable member and the front plate 16 of the stationary member.

65 The bottom portion of the entrance way

to this storage space 64 is controlled by a guard 66 which prevents free movement of the lower ends of the clothes bars 14 out of the storage space, although they can be moved out in obvious manner by hand manipulation.

In operation of the device the mechanism is installed in its desired position with all the parts in the position of Fig. 1. When the operator desires to do so, he manipulates latch 28 and crank 26 to raise member 10 and attached parts to any desired position and secures it in place. He then takes hold of the clothes bar 14 at the left of the storage space 64, as viewed in Fig. 3, swings 75 its lower end out past guard 66 and then moves its loop 52 up frame portions 60 and 58 to portion 54, and thence to curve 54^a until he has bar member 14 in desired position, preferably somewhere near that of bar member 14^a, shown in Fig. 2. He repeats this operation with the succeeding bar members until all those which are provided project like the spokes of a wheel, as shown in Fig. 2, whereupon the bars are 80 ready to be used in drying clothing or other articles placed upon them. When the drying process is completed the operator reverses the order of operations thus described and returns the mechanism to the position of 90 Fig. 1.

Having thus described my invention, what I claim as new and desire to secure by Letters Patent, is:

1. The combination of a suitable hollow 100 case adapted to receive through a suitable opening in one wall, a plurality of rigid clothes bars adapted to be moved from a position in the case to a position outside the case where they extend therefrom, and a 105 trackway mounted substantially inside the case engaged by the end portions of said clothes bars adapted to guide and control said clothes bars in all positions of their said movement.

2. In a device of the class described, a generally vertical case provided with an elongated slot therein permitting the entrance of clothes bars therethrough, a generally horizontal supporting member extending across the interior of the case adapted to receive and support clothes bar members entering the case, a plurality of clothes bar members suspended from said cross member, means on the outer ends of said cross 115 member preventing the free movement of the clothes bar members out of the case, and spring means within the case urging the clothes bar members outward.

3. In a device of the class described, a 125 generally vertical case having a slot on one side forming an entrance for clothes bar members, a plurality of clothes bar members adapted to enter the case through said slot and lie in a substantially vertical po- 130

sition inside the case, a cap or hood at the top of the case of approximately semi-circular cross-section having in its outer vertical face an elongated slot within which 5 the ends of clothes bar members may enter said hood, and a continuous supporting member for the clothes bar members extending transversely of the case to support the clothes bar members in the case, thence 10 into the hood to retain the ends of the same clothes bar members inside the hood, the whole so shaped and arranged that the clothes bar members may be moved from suspended concealed position in the case to 15 a position wherein they project from the hood in a plane at right angles to the general length of the case and are supported for clothes drying purposes, for the purposes set forth.

20 4. A track member and a plurality of clothes bar members slidably suspended

upon the track member, said track member formed in two continuous parts lying at different horizontal levels its lower portion being adapted to suspend a plurality of 25 clothes bar members in substantially a common vertical plane, and its upper portion being adapted to retain said clothes bar members in such a position that they radiate from substantially a common center at right 30 angles to their first mentioned position, this in combination with means for supporting the clothes bar members in said radial position.

In witness whereof, I have hereunto sub- 35 scribed my name in the presence of two witnesses.

CARTER W. SINGLETERRY.
